[57] **CLAIM**

The ornamental design for an orthopedic pillow, as shown and described.

DESCRIPTION

FIG. 1 is a front perspective view of the orthopedic pillow, showing my new design;

FIG. 2 is a top plan view thereof;

FIG. 3 is a right side elevational view thereof with the two sides being the same;

FIG. 4 is a front elevational view thereof;

FIG. 5 is a rear elevational view thereof; and,

FIG. 6 is a bottom plan view thereof.

The cross-hatching represents conventional fabric and is understood to extend throughout the areas represented.
